(57) **CLAIM**

The ornamental design for a user interface for display screen, as shown and described.

DESCRIPTION

©2003 Apple Computer, Inc.

A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyright rights whatsoever.

FIG. 1 is a front view of a user interface for a display screen showing my new design; and,

FIG. 2 is a front view of a second embodiment thereof, the user interface being shown separately for clarity of illustration, on an enlarged scale.

The broken line drawing in FIG. 1 of a display screen, the interior square and circular elements are for illustrative purposes only and form no part of the claimed design.
